[57] CLAIM

The ornamental design for an X-ray cable connector, as
shown and described.

DESCRIPTION

FIG. 1 is a front elevational view of the X-ray cable
connector showing my new design;

FIG. 2 is a fragmentary cross-sectional view thereof
taken along line 2—2 of FIG. 1 with the connector
shown rotated 90°;

FIG. 3 is an exploded perspective view thereof showing
the central mating portions, the remaining portions of
the connector being omitted for illustrative purposes
only.
